UNITED STATES PATENT OFFICE.

FREDSON E. BOWERS, OF NEW HAVEN, CONNECTICUT, ASSIGNOR TO THE F. E. BOWERS CO., OF NEW HAVEN, CONNECTICUT, A CORPORATION.

CARBURETER FOR GASOLENE-ENGINES.

No. 850,339.

Specification of Letters Patent.

Patented April 16, 1907.

Application filed July 28, 1906. Serial No. 328,171.

To all whom it may concern:

Be it known that I, FREDSON E. BOWERS, a citizen of the United States, residing at New Haven, in the county of New Haven 5 and State of Connecticut, have invented a new and useful Improvement in Carbureters for Gasolene-Engines; and I do hereby declare the following, when taken in connection with the accompanying drawings, and 10 the letters of reference marked thereon, to be a full, clear, and exact description of the same, and which said drawings constitute part of this specification, and represent, in—

Figure 1, a side view of a carbureter constructed in accordance with my invention and shown in its relation to the usual float-chamber and throttle-valve. Fig. 2 shows the carbureter in vertical central section and in its relation to the usual float-chamber; 20 Fig. 3, a vertical central section through the carbureter in a line at right angles to Fig. 2.

My invention relates to an improvement in carbureters for gasolene-engines, the object being to produce a simple and compact device constructed with particular reference to automatically proportioning the respective amounts of air and gasolene in the mixture according to the requirements of the work to be done and to securing a more perfect mingling of the gas and air under all conditions. 30

With these ends in view my invention consists in a carbureter having certain details of construction and combinations of parts, as will be hereinafter described, and particularly recited in the claims.

In carrying out my invention as herein shown I employ a conical upper shell 8 and a conical lower shell 7, located one above the other in a cylindrical outer shell 2, a concentric vacuum-chamber 2^a being formed between the inner surface of the outer shell 2 and the outer surfaces of the upper and lower shells 7 and 8. The conical shells 7 and 8 are arranged with their smaller ends adjacent, 45 and the lower end of the upper shell being larger in diameter than the upper end of the lower shell an annular intake-space 2^b is formed between them. As shown, the upper shell is furnished at its lower end with an outwardly-flaring flange 12, corresponding in pitch to the pitch of the lower shell, so as to produce a conical air-passage 2^c, leading to the said intake-space 2^b. A spray-nozzle 6, located in the center of the upper end of the

lower shell 7, is mounted in a supply-pipe 5, 55 leading from a float-chamber 3, containing the float which controls the amount of gasolene fed to the spray-nozzle. A throttle-valve 4 of any approved construction is located upon the top of the outer shell 2 and 60 receives the mixture from the upper end of the upper shell 8. At opposite points in the sides of the outer shell 2 I form air-ports 9, normally closed by valves 10, controlled by springs 11. Air is also taken through the 65 lower end of the lower shell.

The operation of my improved carbureter is as follows: The engine being started in the usual manner, gasolene is drawn from the float-chamber 3 through the pipe 5 into the spray-nozzle 6, from which it is sprayed into the upper shell 8, where it is mixed with currents of air rising through the lower shell. The resulting suction in the upper shell creates a vacuum in the concentric vacuum-chamber 2^a. The greater the speed of the engine the greater the suction in the upper shell 8, and hence the more the rarefaction of the air in the vacuum-chamber 2^a. At a predetermined point in the speed of the engine the suction produced by its action will 75 overcome the power of the springs 11 and allow the valves 10 to open so as to permit air to rush into the vacuum-chamber 2^a and thence enter the upper shell 8 through the 80 inclined annular air-passage 2^c and air-intake space 2^b at such an inclination to the gasolene rising in spray or jets from the nozzle 6 that the air will so intersect the spray that a perfect commingling of air and 85 gasolene will result without increasing the flow of gasolene, for the reason that the admission of air through the air-ports 9 into the vacuum-chamber 2^b will decrease the pressure of air drawn upward through the lower 90 chamber, and hence slightly decrease the amount of gasolene fed. The air rushing in through the ports 9 will almost immediately restore the balance of pressure and permit the springs 11 to close the valves 10, which 95 will, as described, open and close automatically according to the fluctuations of pressure within the device produced by changes in the speed at which the engine drawing on the carbureter for its supply of vapor is run 100 or by changes in the amount of work the engine is called upon to do. The location of the valves 10 opposite each other equalizes

the air-pressure in the vacuum-chamber 2^a, so that the air rushing through the passage 2^c and space 2^b into the upper shell will be at every point under equal pressure and insure a uniform and perfect commingling of the air and vapor.

I claim—

1. In a carbureter, the combination with an upper shell and a lower shell made independent of each other and constructed and arranged to form an air-intake space between their adjacent ends, of an outer shell inclosing the said upper and lower shells and forming a concentric vacuum-chamber about the same, a spray-nozzle entering the said lower shell, and means for automatically controlling the entrance of air into the said chamber from which the air enters the said upper shell through the said air-intake space.
2. In a carbureter, the combination with a tapering upper and a tapering lower shell made independent of each other, the former being made larger in diameter than the latter to produce an annular air-intake space between their adjacent ends, of an outer shell inclosing the said upper and lower shells and forming a concentric vacuum-chamber about the same, a spray-nozzle entering the lower shell, and means for automatically controlling the entrance of air into the said vacuum-chamber.
3. In a carbureter, the combination with a tapering upper and a tapering lower shell having an air-intake space between them, an annular flange located at the lower end of the upper shell and producing an inclined annular passage leading to the said air-intake space, an outer shell inclosing the said upper

and lower shells and forming a concentric vacuum-chamber about the same, a spray-nozzle entering the lower shell, and means for automatically controlling the entrance of air into the said vacuum-chamber.

4. In a carbureter, the combination with a tapering upper and a tapering lower shell, the former being made larger in diameter than the latter to form a concentric air-intake space between their adjacent ends, of an outer shell inclosing the said upper and lower shells and forming a concentric vacuum-chamber about the same, and two or more valves automatically controlling the inlet of air into the said vacuum-chamber and arranged to equalize the air-pressure therein.

5. In a carbureter, the combination with a conical upper shell, the upper shell being made larger in diameter than the lower shell for the production of an annular air-intake space between the two shells, an outwardly-flaring flange located at the lower end of the upper shell and extending down over the upper end of the lower shell to form an inclined air-passage leading to the said air-intake space, an outer shell inclosing the upper and lower shells and forming a vacuum-chamber around the same, a spray-nozzle entering the lower shell, and means for automatically controlling the inlet of air into the said vacuum-chamber.

In testimony whereof I have signed this specification in the presence of two subscribing witnesses.

FREDSON E. BOWERS.
